UNITED STATES PATENT OFFICE.

JOHN H. HOBBS, OF WHEELING, WEST VIRGINIA.

DESIGN FOR BEER-MUGS.

Specification forming part of Design No. 5,977, dated July 9, 1872.

SPECIFICATION.

To all whom it may concern:

Be it known that I, JOHN H. HOBBS, of Wheeling, in the county of Ohio and State of West Virginia, have invented a new and useful Improved Design for Beer-Mug; and I do hereby declare the following to be a full, clear, and exact description thereof, reference being had to the accompanying drawing, which represents in side elevation my improved design for beer-mug, the same being hereby made a part of this specification.

My improved design consists of a beer-mug or glass of the general form shown, which, in the body B, approximates to that of a vase, except at the upper end, a little above the upper junction of the handle b, which part a tapers slightly inward. Below that part the body tapers inward, vase-like, to a point in

the vertical height of the glass about one-third of its height from the lower end. Then it flares outwardly with somewhat more abruptness to the base or lower end a'. The vase-shaped part is made plain or fluted, or is finished in panels c, as shown. The handle is of the usual form.

What I claim as my invention, and desire to secure by Letters Patent, is—

The design for beer-glasses of a vase-shaped body, tapering inwardly at the upper end, as at a, with a handle, b, substantially as described.

In testimony whereof I, the said JOHN H. HOBBS, have hereunto set my hand.

JOHN H. HOBBS.
